of New York

Application July 25, 1947, Serial No. 140,505

Term of patent 14 years

(Cl. D86—10)

To all whom it may concern:

Be it known that I, Bernard d'Escayrac, a citizen of France, residing in the city, county, and State of New York, have invented a new, original, and ornamental Design for a Lipstick Container or the like, of which the following is a specification, reference being had to the accompanying drawing, forming a part thereof.

Fig. 1 is a top plan view of a lipstick container or the like, showing my new design;

Fig. 2 is an elevational view of the lipstick container or the like illustrated in Fig. 1, showing my new design;

Fig. 3 is a bottom plan view of the lipstick container or the like illustrated in Fig. 1; and

Fig. 4 is a perspective view showing the lipstick container or the like illustrated in Figs. 1, 2 and 3.

The back of the lipstick container is substantially like the front shown in Fig. 2.

I claim:

The ornamental design for a lipstick container or the like, substantially as shown and described.

BERNARD d'ESCAVRAC.
